2 SHEETS—SHEET 2.

Inventor
GEORGE H. HART
By his Attorneys
Bartlett Browne & Co.

UNITED STATES PATENT OFFICE.

GEORGE H. HART, OF WEST HARTFORD, CONNECTICUT.

ELECTRIC SWITCH.

1,222,947.

Specification of Letters Patent. Patented Apr. 17, 1917.

Application filed June 17, 1916. Serial No. 104,180.

To all whom it may concern:

Be it known that I, GEORGE H. HART, a citizen of the United States, residing at West Hartford, county of Hartford, State of Connecticut, have invented certain new and useful Improvements in Electric Switches, of which the following is a full, clear, and exact description.

My invention relates to electric switches, and has for its object to provide a snap switch which can be operated to make and break a circuit by an oscillating movement of the actuating member. It further has for its object to produce such a switch in which the actuating member is capable of a complete revolution in one direction, making and breaking a circuit a plurality of times during a continued movement of revolution in one direction.

20 A further object of my invention is to provide an oscillating switch with a removable handle fixed against rotation relatively to the spindle in either direction and adapted to hold the cover of the switch in place 25 with a yielding spring pressure.

The following is a description of an embodiment of my invention, reference being had to the accompanying drawings, in which:

30 Figure 1 shows a plan view of a switch embodying my invention;

Fig. 2 is a section on line 2—2, Fig. 1;

Fig. 3 is a plan view of the base and portions directly carried thereby;

35 Fig. 4 is a detail of the stops and carrying member;

Fig. 5 is an enlarged perspective view of one stop;

Fig. 6 is a side elevation of the spindle 40 and parts carried thereby. Fig. 6^a is a section on line 6—6 Fig. 6.

Fig. 7 is a bottom view of the parts shown in Fig. 6.

Fig. 7^a is a section of the handle.

45 Figs. 8 to 12 are plan views of portions illustrating various steps in the operation of the switch.

Referring more particularly to the drawings, 1 is a switch base made of insulating material, 2 is a spindle-carrying-member having a chamber 3 and radial grooves which in the present instance are separated by 90°. This spindle-carrying-member is secured to the base by a nut 5. In the radial 50 grooves are two stop pins 6—6' of L-shape, their inner ends being provided with a cam

surface 7 whose high point corresponds with the medial line of the stop pin. 8 is a spindle revolvably mounted in said spindle-carrying-member 2 and secured therein by a clip 9. This spindle carries two fixed thrust members 10—10, separated by 180° in the present embodiment. This angular separation depends on the angular displacement of the two stop pins and is 180° when said stop pins are spaced 90° from one another. Mounted on the spindle immediately above the cams 10—10 and movable relatively thereto is a stop plate 11, whose periphery is provided with recessed portions so as to form equally spaced shoulders 12, the shoulders in the present instance being displaced from one another by 90°. On the upper end of the spindle 8 is a handle 13, said handle being provided with an internal 75 bushing 14 which carries an internally screw-threaded socket 14', the bushing and socket being provided with angular surfaces so as to prevent the rotating of one relatively to the other and to the body of 80 the handle. The body of the handle is molded about the bushing, which is held within the body of the handle so as to be fixed relatively thereto by the projection 15 extending into a recess in the handle. The 85 bushing is provided upon its face with a notch 16 which notch engages projections 17 upon a plate 18 which is secured to the spindle. By these means the handle can be secured on the spindle, being screwed thereon, and then held from turning in either direction. In screwing it home it is pulled away 90 from the switch and thereafter released so as to bring the projections 17 upon the plate 18 into engagement with the notch 16 upon the bushing. Such engagement prevents the handle from being turned relatively to the spindle in either direction unless it is drawn away from the plate 18 against the action of the spring 19. The action of the spring 19 95 draws the handle down upon the cover 20, so as to hold the cover in place and hold these notches and projections in engagement. The plate 18 can be applied and removed from the spindle by a lateral motion 105 by reason of the presence of the slot 21 therein. The plane edges of the slot engage parallel faces formed upon the sides of the spindle notches; and the plate 18 is thus held from turning.

110 Spring ends 22 bearing upon the stops 6—6' normally tend to move the stop pins

toward the center of the switch and to hold them in line with the projections 12 upon the stop plate member. These spring ends are formed by a broken spring ring which lies in a groove in the periphery of the member 3. The pin 23 standing in the paths of the ends 22 of the spring prevents the ring from moving so that its ends will always properly engage the stop pins 6-6'. Rigidly connected to but insulated from the stop plate is a switch arm 24, which thus moves with it step by step. 25-25 are contacts which are engaged and disengaged by the switch arm as it makes the successive steps. The switch 15 arm is moved with a snap-action by the spring 26, whose two ends embrace studs 27 and 28, connected to the spindle and stop-plate respectively in the well known manner. This spring restores the parts to normal 20 position (Figs. 8 or 12) if the handle is moved somewhat but not enough to actuate the switch arm. Thus when the parts are in the position shown in Fig. 10 the distended spring 26 will restore them to the 25 position shown in Fig. 8, the pin 6 being again moved outwardly during the returning movement of the spindle.

The action of the switch is as follows: When the parts are in the position shown in Fig. 8 a clock-wise movement of the handle causes a thrust member to move the stop pin 6 outward. This is an idle movement. After the thrust member has passed the cam surface upon this stop pin 6, it engages the cam surface on the next stop pin 6' and forces it outward. This removes the second stop pin 6' from a restrained shoulder of the stop plate member which then swings around and until the second preceding shoulder engages the stop pin 6 which is now returned to its normal position, as shown in Fig. 12. A further movement of the handle in the same direction causes a thrust member to move the stop pin 6' outwardly, an idle 40 movement, and causes a thrust member to then move the stop pin 6 outward so to release the shoulder that it has been restraining, permitting the stop plate member to revolve another 90° until the same shoulder 45 engages with the stop pins 6', as shown in Fig. 8. A reverse movement of the handle produces reverse results.

A thrust member after it has forced out a stop pin, so as to release the stop plate, normally moves backward, so as to lie behind that stop pin, this being due to the action of the spring 26. When the outer ends of the two stop pins lie in the same cutaway portion a thrust member lies between their inner ends when the parts are in normal position. When the outer ends of two adjacent stop pins are on opposite sides of a projection on the stop plate, there is no thrust member between them or between their inner ends. The movement of the stop pin

first acted upon is always an idle movement when the movement of the parts are in normal position.

As will be evident to those skilled in the art, my invention permits of various modifications without departing from the spirit thereof or the scope of the appended claims.

What I claim is:

1. In a snap switch capable of being actuated by an oscillating movement, the combination of a base, a spindle-carrying-member thereon having a plurality of radial recesses, stop pins located in said recesses and having inner cam surfaces, a spindle movably mounted in said spindle-carrying member, thrust members fixed on said spindle and adapted to engage said cam surfaces and a stop plate revolvably carried by said spindle and provided with alternate cutaway portions and projections forming substantially equally spaced shoulders adapted to engage said stop pins, a stop plate actuating spring, and means for holding said stop pins in shoulder-engaging position, the cam surfaces of two pins being separated by the axis of one of said thrust members when their outer ends are in the same cutaway portion of said plate. 75 80 85 90

2. In a snap switch capable of being actuated by an oscillating movement, the combination of a base, a spindle-carrying-member thereon having two radial recesses, stop pins located in said recesses and having inner cam surfaces, a spindle movably mounted in said spindle-carrying member, a plurality of thrust members fixed on said spindle and adapted to engage said cam surfaces, a stop plate revolvably carried by said spindle and provided with alternate cutaway portions and projections forming substantially equally spaced shoulders adapted to engage said stop pins, a stop-plate actuating spring, means for holding said stop pins in shoulder-engaging position, the angles between said recesses being substantially one-half of the angle between said thrust members, the cam surfaces of two pins being separated by the axis of one of said thrust members when their outer ends are in the same cutaway portion of said plate. 100 105 110 115

3. In a snap switch capable of being actuated by an oscillating movement, the combination of a base, a spindle-carrying-member thereon having a plurality of radial recesses, stop pins located in said recesses and having inner cam surfaces, a spindle movably mounted in said spindle carrying member, two thrust members fixed on said spindle adapted to engage said cam surfaces successively and a stop plate revolvably carried by said spindle and provided with alternate cutaway portions and projections forming substantially equally spaced shoulders adapted to engage said stop pins, means for holding said stop pins in shoulder-en- 120 125 130

gaging position, the cam surfaces of two pins being separated by the axis of one of said thrust members when their outer ends are in the same cutaway portion of said plate, said recesses being located at an angle of 90° from each other and said thrust members being located at an angle of substantially 180° from each other.

4. In an electric switch capable of being actuated by an oscillating movement, the combination of a spindle, a holding plate thereon, a handle, a bushing fixed in said handle, an internally threaded socket within said bushing movable longitudinally but not axially relatively thereto, a spring retracting said socket within said bushing,

said plate having a radial slot engaging the sides of said spindle and being removable from said spindle by a movement parallel to said slot, said spindle and plate having 20 plane surfaces engaging so as to prevent their relatively axial movement in either direction, said plate and bushing being provided with stop surfaces located at an angle to the walls of said slot preventing axial 25 movement of said bushing relatively to said plate and spindle and preventing said plate moving relatively to said spindle in a direction parallel to its slot when said surfaces are in engagement said bushing locking said plate upon said spindle.

GEORGE H. HART.
